UNITED STATES PATENT OFFICE

163,807

SCHOOLBAG

Sholom E. Kaplan, Hartford, Conn.

Application June 28, 1950, Serial No. 10,817

Term of patent 14 years

(Cl. D87—3)

To all whom it may concern:

Be it known that I, Sholom E. Kaplan, a citizen of the United States, residing at Hartford, in the county of Hartford, State of Connecticut, have invented a new, original, and ornamental Design for a Schoolbag, of which the following is a specification, reference being had to the accompanying drawing, forming a part hereof.

In the accompanying drawing:

The figure is a front view, slightly in perspective, of a schoolbag showing my new design, the back of the bag being plain and the dominant feature of the design residing in the specific ornamentation on the front.

I claim:

The ornamental design for a schoolbag, substantially as shown and described.

SHOLOM E. KAPLAN.
